UNITED STATES PATENT OFFICE.

GEORGE B. BUCK, OF NEW YORK, N. Y., ASSIGNOR TO THE TABULATING MACHINE COMPANY, OF WASHINGTON, DISTRICT OF COLUMBIA, A CORPORATION OF NEW JERSEY.

VERIFYING-PUNCH.

1,266,768.

Specification of Letters Patent. Patented May 21, 1918.

Application filed July 25, 1916. Serial No. 111,204.

To all whom it may concern:

Be it known that I, GEORGE B. BUCK, a citizen of the United States, residing at New York, in the county and State of New York, 5 have invented certain new and useful Improvements in Verifying-Punches, of which the following is a full, clear, and exact description.

This invention relates to certain new and 10 useful improvements in verifying punches.

In tabulating machine work data are tabulated by punching differentially spaced holes on record cards. The machine for carrying out the punching operation may be 15 the Hollerith machine shown in Patent No. 682,197. In this machine, the punching operation is performed by depressing certain keys. Operators using the machine sometimes depress the wrong key and incorrect 20 data are then tabulated upon the card. It has therefore been found that usually the punched cards must be checked to determine if any errors have been made. Previously 25 this checking has been done by a visual inspection of the cards but this method of checking has been found unsatisfactory as the checker is liable to make the same error that was originally made by the operator who punched the card. Also the visual 30 checking is a tedious and time-consuming operation.

The present invention is directed to a machine in which the punched cards may be placed and the errors detected. The operation 35 of checking is exceedingly rapid and the possibility of checkers' errors being identical with punching operators' errors is largely eliminated.

The checking machine or verifying punch 40 as it is preferably called is provided with keys similar to those in the card punching machine and the checker operates the keys just as if a new card were being punched. If the card is correctly punched the record 45 card table or carrier feeds forward upon the depression of each key; but if a punch hole is incorrectly spaced in the card, the carrier does not feed forward thereby apprising the checker of the error in the card.

50 In the drawings:

Figure 1 is a top plan view of the verifying punch;

Fig. 2 is a sectional view taken on line 2—2 of Fig. 1;

Fig. 3 is an enlarged detail view of the 55 escapement mechanism for the record card carrier;

Fig. 4 is a detail sectional view of the escapement mechanism taken on line 4—4 of Fig. 3;

Fig. 5 is a detail view of a part of escapement operating devices and shows in detail the operation of the escapement shaft from the bail operated by the numeral keys;

Fig. 6 shows the operation of a key and 65 associated parts when the hole in the card is correctly positioned.

Fig. 7 shows the operation of the parts when the hole is incorrectly positioned in 70 the card.

Fig. 8 is a detail view showing one of the punched record cards;

Fig. 9 is a detail showing the connections for operating the escapement and the tabulating ratchet-shifting mechanism;

Fig. 10 is a side view of the escapement ratchet and shows the tabulating ratchet.

In more detail in Figs. 1, and 2, 10 is the base of the machine which slidably supports the reciprocating record card carrier 80 11. The record card 12 (see Fig. 8) is placed between guides 13 in the frame of the machine and the ends of the cards come into contact with abutments 14 on the carrier. As the carrier is reciprocated the card 12 is 85 slid back and forth as in the Hollerith machine. The card carried is moved in one direction by a motor spring M (see Fig. 4) which connects with the carrier 11 through gear 15, pinion 16, shaft 17, pinion 18 and 90 rack 19. The numeral keys K are mounted to slide vertically in frame members as shown in Figs. 3, 6 and 7, and these keys K when depressed are adapted to rock levers 20. It will be understood that there is one 95 lever 20 for each key as shown in Fig. 1. The levers differ from those in the Hollerith machine in several respects. In the Hollerith machine the levers are fulcrumed at their ends upon fixed fulcrum points and 100 upon being rocked were adapted to rock a bail downwardly which bail served to operate the escapement mechanism controlling the movement of the carrier. In the pres-

ent embodiment, the ends of the levers 20 bear against fulcrum pins 21, which pins are spring pressed downwardly by springs 22 which press against collars on the fulcrum pins and at their upper ends against a casing as shown in Fig. 2.

Intermediate the fulcrum pin 21 and the keys K, the levers 20 rest upon the top of a bail 24 which is pivotally mounted on the 10 frame of the machine and upon the shaft 25. The bail 24 has a projecting portion 26 (see Figs. 5 and 9) which is adapted to rock a sleeve member 27 in a counter clockwise direction when the bail is depressed. The 15 sleeve member is normally restored by a spring shown in Fig. 5 and this sleeve has secured to its end a pawl 28.

The pawl 28 carries a pin 29 which loosely engages in a hole in a retaining dog 31 which 20 dog is normally held in engagement with the ratchet teeth on ratchet wheel 30 by means of a spring. As in the Hollerith punching machine the depression of a key rocks the bail 24 and through 27 rocks pawl 25 28 into engagement with the ratchet and retaining dog 31 out of engagement. Then on the release of the key the pawl 28 rocks out and dog 31 moves into engagement. Meanwhile the ratchet has fed forward one 30 step under the power of the main spring M. The ratchet 30 is connected with the gear 15 and thereby controls the movement of the card carrier.

The escapement mechanism is also provided with a supplementary ratchet 32 having certain teeth cut away as shown in Fig. 10 and the retaining dog is adapted to be shifted to this ratchet when desired by depressing a special key K^x. Lever 20^x will 40 then depress part 33, thereby through tail 34 rocking rock member 34^a and through link 35 forcing dog 31 to the outside ratchet 32. At the same time a lug 36 will rock the sleeve member 27 and the pawl and dog will then 45 operate to permit the escapement action to take place. After the special key K^x has been operated, the depression of another numeral key K will, through tail 38 depending from bail 24, rock 34^a in a reverse direction to restore the retaining dog to the inner ratchet 30. The retaining dog can be 50 released from either ratchet wheel by depressing the release key L.

These parts are all present in the Hollerith punching machine and need not be described in further detail here. It is sufficient to state that the feed of the card carrier takes place upon the upward rocking of bail 24, and that by reason of the clearance 60 between the pin 29 and the edges of the hole in the retaining dog 31, the bail 24 can be slightly depressed without operating the escapement and without permitting the card carrier to move under the influence of the 65 motor spring.

The devices which permit the carrier to move if the card is correctly punched and which prevents such movement if the card is incorrectly punched, will now be described.

Beneath each of the key levers 20 (also 70 20^x) and intermediate the bail 24 and the spring fulcrum plungers 21 are a series of buttons 40. Each of these buttons carries a downwardly extending detecting punch or pin 41 and the pins and buttons are normally held in upper position in the machine frame by springs 42 (see Fig. 6). The detecting pins extend in a straight line across the machine and occupy the same relative position therein as the perforating punches in the 75 card punching machine. In fact their construction is identical except that the lower ends are slightly rounded so as not to mutilate the card 12.

In case a card is correctly punched, the 80 depression of the correct key K will rock lever 20 downwardly about the lower end of plunger 21 as a fulcrum, the detecting pin 41 will pass through the hole in the card, and bail 24 will be rocked downward to 90 such an extent that upon the release of the key K, the escapement will operate and the card carrier will advance in the manner heretofore described. The operation showing the detecting punch or pin passing 95 through the hole in the card is illustrated in Fig. 6.

However if the hole has not been properly 100 punched in the card, or if the wrong key K is operated, the lever 20 or 20^x will first be rocked about 21 as a fulcrum and the bail 24 will be rocked slightly as shown in Fig. 7. As soon as the detecting pin 41 comes 105 into contact with the card 12 the fulcrum of the lever changes—button 40 becomes the fulcrum of the lever thereby elevating the plunger 21 against the tension of its spring. By reason of the changed position of the fulcrum of the lever 20, the bail 24 is only 110 rocked to a slight extent by the further depression of the key and this movement is not sufficient to lift the retaining dog from its co-operating ratchet. Therefore upon release of the key K no feed of the card carrier takes place. This immediately indicates to the 115 checker that there is a mistake in the card or that he, the checker, has depressed the wrong key in the verifying machine. If the latter is the case, the checker can immediately correct his mistake by depressing the correct 120 key. If the card carrier still does not feed, the checker knows that the card is incorrect and he can then remove it from the machine and mark the error so that a new and correct card can be made.

By the use of this verifying punch the 125 operation of checking cards can be carried out with greater facility and double errors of both punching and checking are very largely eliminated.

It is to be understood that my invention is not limited to the particular embodiment shown and described but that what I claim as my invention is more particularly pointed out in the appended claims.

5 I claim:

1. In a machine of the class described, in combination, a support for a punch card; a series of keys; a series of pins for registering with the holes in said card; operative connections between each of said keys and one of said pins; and means for indicating the failure of any pin, when actuated by a key, to register with a hole in said card.
- 10 2. In a machine of the class described, in combination with a support for a punched card; a series of keys; a series of pins for registering with the holes in said card; operative connections between each of said keys and one of said pins; and means for indicating the registration of a pin with a hole upon the actuation of the proper key.
- 15 3. In a machine of the class described, in combination with a support for a punched card; a series of keys; a series of pins for registering with the holes in said card; operative connections between each of said keys and one of said pins; means for indicating the registration of a pin with a hole in the card upon the actuation of the proper key; and means for indicating the failure of any pin to register with a hole in the card upon the actuation of a key.
- 20 4. In a machine of the class described, in combination with a card carrier to receive a punched card and advance the same; a plurality of keys; mechanism operated thereby and adapted to coöperate with the card; a means for advancing the card carrier; and means operable when the key operated mechanism registers with a hole in the card, to permit the advance of the card carrier, said means being inoperative to permit the advance of the card carrier upon the non-registration of the key actuated mechanism and the hole in the card.
- 25 5. In a machine of the class described, in combination with a card carrier adapted to receive a punched record card and having provisions to advance the same; a plurality of keys; mechanism operated thereby and adapted to coöperate with the record card; means to control the advancing movement of the card carrier; and means to control the effective operation of the said controlling mechanism upon the registration or non-registration of the key-operated mechanism and a hole in the card.
- 30 6. In a machine of the class described, in combination with a card carrier adapted to receive a punched record card, and having provisions to advance the same; means to control the advance of the card carrier; a plurality of keys; key-operated mechanism
- 35 in coöoperative relation to the punched card;

and means associated therewith to operate the controlling mechanism to permit the advance of the card carrier upon a registration of the key-actuated mechanism and a hole in the card, said means being ineffective to 70 permit the advance of the card carrier when the key-actuated mechanism does not register with the hole in the card.

7. In a machine of the class described, in combination with a card carrier adapted to receive a punched record card, and having provisions to advance the same; means to control the advance of the card carrier; a plurality of keys; key-operated mechanism in coöoperative relation to the punch card; 80 and means associated therewith to prevent the effective operation of the controlling mechanism upon the non-registration of the key-actuated mechanism and the hole in the record card, whereby the card carrier is not 85 advanced when such non-registration occurs.

8. In a machine of the class described, in combination, a card carrier adapted to receive a punched record card; a series of verifying pins disposed adjacent to the card; 90 keys to operate the same; a driving means for the card carrier; an escapement mechanism; and means, operable upon the actuation of a key and upon a verifying pin passing through a hole in the card, to operate 95 the escapement and permit the driving means to advance the card carrier.

9. In a machine of the class described, in combination, a card carrier adapted to receive a punched record card; a series of verifying pins disposed adjacent to the card; 100 keys to operate the same; a driving means for the card carrier; an escapement mechanism; and means, operable upon the actuation of a key, to operate or prevent the operation of the escapement in accordance 105 with the passing or non-passing of a verifying pin through a hole in the card.

10. In a machine of the class described, in combination, a card carrier adapted to receive a punched record card; a driving means therefor; an escapement to control the movement of the card carrier; a series of verifying pins disposed adjacent the record card; a series of operating keys; a series of 110 levers, each of said levers depressing one of the verifying pins upon the depression of a key; means for varying the fulcrum of the said levers when the depressed pin contacts with the card, said fulcrum maintaining its 120 position when the verifying pin passes through a hole in the card; and means operable to release the escapement when the fulcrum remains fixed, said means being inoperative to release the escapement when the 125 fulcrum of the lever varies.

11. In a machine of the class described, in combination, a card carrier adapted to receive a punched record card; a driving means therefor; an escapement to control the 130

movement of the card carrier; a series of verifying pins disposed adjacent the record card; a series of operating keys; a series of levers operated by the keys, each of said levers being adapted to depress one of the verifying pins upon the operation of a key; means for varying the fulcrums of said levers when the depressed pin contacts with the record card, said fulcrum maintaining its position when the verifying pin passes through a hole in the record card; a bail operated by the levers and having operating connections with the escapement to operate

the same, said bail being adapted to be moved sufficiently to operate the escapement 15 when the fulcrum remains in position and said bail having insufficient movement to operate the escapement when the fulcrum shifts.

In testimony whereof I affix my signature 20 in the presence of two subscribing witnesses.
